his Attorney.

UNITED STATES PATENT OFFICE.

CHARLES E. DAVIS, OF COLUMBUS, OHIO.

TLTING-CHAIR.

SPECIFICATION forming part of Letters Patent No. 357,183, dated February 8, 1887.

Application filed July 15, 1886. Serial No. 208,160. (No model.)

To all whom it may concern:

Be it known that I, CHARLES E. DAVIS, a citizen of the United States, residing at Columbus, in the county of Franklin and State of Ohio, have invented certain new and useful Improvements in Tilting-Chairs; and I do hereby declare the following to be a full, clear, and exact description of the invention, such as will enable others skilled in the art to which it appertains to make and use the same.

My invention relates to improvements in chairs having a stationary seat and spring back. The seat may have four legs, one in each corner, as a common chair, or it may be secured 15 to a screw, as in piano and office chairs having only a rotary motion, and not to chairs having a tilting seat, as in tilting-chairs.

The object of my invention is to provide a chair having a back so arranged in connection with a spring that it conforms to different positions when it is occupied by a person sitting in the chair and leaning backward, thereby forming a back-rest. I attain this object by the mechanism illustrated in the accompanying 25 drawings, in which—

Figure 1 represents a side (left) view of chair, dotted lines representing chair in position when occupied, with the back pressed backward. Fig. 2 represents the bottom of the 30 chair as viewed from underneath. Fig. 3 represents the chair as viewed from the front, showing lifting-lever.

Similar letters refer to similar parts throughout the different views.

35 A is a stationary seat; B, an arm, one part passing around parallel with the edge of the seat, the other part joining the back about half-way up from the seat, both parts being fastened to the back, both arm and back working 40 on a pivot at the side of the seat, which passes through the lower part of the arm and directly into the side edge of the seat; L, a cross-piece secured to the under side of the arms and rests on the spring F.

C is a plate secured to the seat, in which the 45 screw D is fastened with a set-screw, c'. The spring F rests upon and is sustained by one arm of a lever, E, which lever is supported by a pivotal bearing, N, the other arm of which is supported and held by the regulating-lever G. 50

M represents bearings for the regulating-lever G. To one arm of lever G is secured a rod, H, which extends through a lug, O, at the side of the seat. One end of this rod is provided with a screw-thread and nut, which sets in an angular depression in one arm of the lever G, to prevent it from turning, and the opposite end is secured by means of a knob rigidly attached thereto and bearing against the outer face of the lug O. By turning the 55 knob H to the right or left the thread upon the end of the rod operates within the nut O and varies the tension of the spring for the purpose of increasing and diminishing the resistance to the back P.

I do not herein claim to be the inventor, broadly, of a chair having a stationary seat in combination with a back adapted to move in the arc of a circle and provided with springs, whereby the back will conform to the different 60 positions assumed by the occupant of the chair.

What I claim as my invention, and wish to secure by Letters Patent, is—

The combination, in a chair, of a stationary 75 seat, a back with arms pivoted thereto, said back resting on and supported by a coil-spring, which is in turn supported by one arm of a lever, having pivotal bearings secured to the seat portion of the chair, the other arm of said 80 lever being attached to mechanism for regulating the tension of the spring, substantially as described.

CHARLES E. DAVIS.
